UNITED STATES PATENT OFFICE.

PATRICK H. MCGRATH, OF WOLLASTON, MASSACHUSETTS.

LINE-INDICATING MECHANISM FOR TYPOGRAPHICAL MACHINES.

1,118,298.

Specification of Letters Patent. Patented Nov. 24, 1914.

Application filed January 15, 1913. Serial No. 742,268.

To all whom it may concern:

Be it known that I, PATRICK H. MCGRATH, a citizen of the United States, residing at Wollaston, in the county of Norfolk and State of Massachusetts, have invented certain new and useful Improvements in Line-Indicating Mechanism for Typographical Machines, of which the following is a specification.

10 This invention relates to line-indicating mechanism for typographical machines, one of the primary objects of the invention being to provide simple and effective means of this character by which the progress of a line can be readily and instantly noted by the compositor or operator of the machine.

In the drawings accompanying and forming part of the present specification I have shown in detail one of the several forms of embodiment of the invention which to enable those skilled in the art to practise the same will be fully set forth in the following description. I do not, however, limit myself to this disclosure; I may depart therefrom in several respects within the scope of the invention defined by my claim following said description.

Referring to said drawings: Figure 1 is a perspective view of a portion of a typographical machine provided with line-indicating mechanism involving my invention. Fig. 2 is a detail view of the indicator shown in Fig. 1.

Like characters refer to like parts in both views, which it will be observed are on different scales.

The present mechanism can be built as a permanent part of a typographical machine or can be easily and quickly attached to any of the existing typographical machines. In Fig. 1 of the drawings I have represented certain of the parts of the well-known Mergenthaler typographical machines. At the present time the operator of such a machine has to raise his eyes to the assembler slide to observe the progress of the line. One of the important features of my improvements, is in the fact that he can be instantly apprised of the condition of the line without the necessity of raising his eyes from the keyboard or the copy which is an advantageous consideration particularly when the copy is fine reprint or largely composed of initials and figures.

55 As is well-known the strain on the eyes is continually searching for the place in

the copy, is considerable but by my device, as will hereinafter appear, I avoid this disadvantage. Said device comprises an indicator between the space bar and the tray or equivalent copy-carrier, and means operative with the assembler-slide, for actuating the indicator, which latter may vary radically in character, the same applying to the means for effecting the operation of the same. It will be clear that when I state that the indicator is "operative with" the assembler-slide, I do not necessarily mean to imply that it is operative or actuated by the same, although I show and prefer to employ this particular relation. As a matter of advantage I prefer to position the indicator of whatever nature the same may be between the lower-case keys of the keyboard and the tray or analogous member, although it might occupy some other position therebetween, the invention not being limited in this respect. There is utility in the location of the line-indicator at the specific place indicated in that the operator usually sits directly opposite the lower-case keys in view of which his efforts are further simplified.

Referring to Fig. 1, 2 denotes the keyboard, 3 the space bar, 4 the tray, and 5 the assembler-slide of the Mergenthaler typographical machine now in every day use; these parts being, therefore, well-known, require no description. The tray 4 is used to receive the copy which is placed directly therein or which may be supported by a copy-holder 6.

As already intimated the kind of indicator is not an essential matter, although the one shown, designated in a general way by 7, and now to be described, answers satisfactorily my requirements. Said indicator includes an elongated casing 8 disposed in the interval between the space bar 3 and the tray 4. Said case may be provided with projections 8' fastened to the under side of the tray or copy carrier. Mounted within said case 8 and preferably near the ends thereof, are sprocket wheels 9 around which is passed the sprocket-chain 10, one link of which may be provided with a line-indicating pointer or finger 11 which as shown extends through a longitudinal slot 12 in the case 8 and adapted to traverse a graduated scale 13 on the outside of said case, the pointer or finger 11 when the assembler-slide 5 is at its extreme backward or re-

tracted position, being opposite the zero-mark of the scale 13. The numbers on said scale, if any be provided, run upward from left to right thereof. The lines or graduations of the scales can of course, bear symbols other than numbers; as a matter of fact none are really required.

As already set forth the indicator is operative with the assembler-slide, the motion of the latter being preferably transferred to the former in any desirable way, although the means shown for this purpose will now be set forth. Fastened to and depending from, the assembler-slide 5 are plates 14 to 5 the lower portions of which, is attached a rack bar 15, the teeth of which mesh with a pinion 16 shown as fastened to the stub shaft 17 supported by a lug or ear 18 on the bracket or fixture 19. A flexible shaft is shown at 20, the lower end thereof being connected with the shaft of the sprocket wheel 9 at the left. Said flexible shaft 20 is adapted for detachable connection with the short stiff shaft 17 by a clamp 21, the 10 sections of which are adapted to be tightened around the adjacent end portions of said two shafts, by the screw 22 having an operating lever or handle 23. When this handle 23 is turned in one direction, the 15 clamp 21 will be disengaged from the shaft 17, while when it is turned in the opposite direction the opposite effect will occur, so that the two shafts 17 and 20 can be operationally connected together, the clamp 21 acting 20 as a convenient form of coupling for this purpose. It will be clear that as the assembler-slide 5 moves, the sprocket-chain 10 through the intermediate parts will be operated, to move the pointer or finger 11 25 forward or backward along the scale 13, the particular motion depending upon the direction of movement of the assembler-slide. Just before the make-up of a line is commenced the assembler-slide will be in its 30 extreme retracted position, the pointer 11 at this time being opposite the zero or initial mark on the scale 13. In the composition of the line the assembler-slide 5 is advanced or moved toward the left in Fig. 1 whereby 35 the pointer 11 through the intermediate parts will be moved in unison step by step with said assembler-slide, so that the operator by glancing at the indicator will be instantly informed of the progress of the line. 40 It will be clear that by the construction described I place within the field of the operator's vision, means by which he is at

once informed of the position of the assembler-slide and naturally of the condition of the line. By "field of vision" I mean that 60 which includes the keyboard and the copy. The Mergenthaler machine is adjusted in most daily newspaper offices to handle six or seven lines a minute, but the compositors who have the ability of operating the machine at this speed are rare. With this type of machine so far as I am aware, there is no way of ascertaining the progress of the line except by looking at the assembler-slide. To do this especially while working 65 on poor copy causes the operator frequently to lose his place and break up the swing or rhythm. On the other hand to over set the line is to run in two or three letters of work and possibly the piling up of a lot of 70 matrices behind the star wheel, and before these have been cleared away the time required to set a half a dozen lines has been lost. When lines are being set at the rate of one in ten seconds, the smallest things are 75 important. By the use of my device I can materially increase the operator's output in that I avoid and eliminate the disadvantages pointed out, while at the same time I make the work easier and relieve to a great extent 80 the eye strain caused by the constant shifting of the eye.

It will be evident from the foregoing description taken in connection with the annexed drawings that my line indicating 90 mechanism involves an indicating element located and movable in a straight path between the space bar and the copy holder and that said indicating element travels in parallelism with said space-bar. 95

What I claim is:

The combination with the space-bar, the copy-carrier, and the assembler-slide of a typographical-machine, of line indicating mechanism having an indicating element located and movable in a straight path between the space-bar and the copy-carrier and adapted to travel in parallelism with said space-bar and means operative with the assembler-slide for actuating said indicating element on the motion of the assembler-slide. 105

In testimony whereof I affix my signature in presence of two witnesses.

PATRICK H. McGRATH.
